UNITED STATES PATENT OFFICE.

CARL E. PETERSON, OF BRIDGEPORT, CONNECTICUT.

BUCKLE.

1,426,905.

Specification of Letters Patent. Patented Aug. 22, 1922.

Application filed January 4, 1922. Serial No. 526,898.

To all whom it may concern:

Be it known that I, CARL E. PETERSON, a citizen of the United States, and a resident of Bridgeport, county of Fairfield and 5 State of Connecticut, have invented certain new and useful Improvements in Buckles, of which the following is a specification.

This invention relates to an improved buckle which is made entirely of wire, which 10 wire is bent to form the frame of the buckle, and while it is symmetrical it is also free from objection, inasmuch as the wire forms an even and smooth bearing for the tongue.

The construction of the frame is such as 15 to give a maximum of stability with a minimum of weight and bulk.

The invention is illustrated in the accompanying drawing, in which Figure 1 is a 20 face view of the buckle. Figure 2 is a side view thereof, and Figure 3 is a section on line 3—3 in Figure 1.

The frame of the buckle is made from a single piece of wire, and the wire forms a central strand 10 which is bent at its ends 25 in opposite directions to form loops on each side of the strand. In the form shown the loops include the end strands 11 and 12, the wire then being bent to form the flanking strands 13 and 14, respectively, and then 30 bent to form the end strands 15 and 16, the ends of the wire being bent around the central strand at its end to form the eyes 17 and 18.

The eyes are preferably placed close to

the strands 11 and 12 so that they are prevented from slipping outward and allowing no spreading of the frame, and it is solid. The tongue 19 is arranged to swing on the central strand, being looped as at 20 to embrace the central strand, the tongue 40 having its free end disposed so as to engage one of the flanking strands, in the drawing the strand 13.

To prevent side movement of the tongue, and to allow it to freely swing, the central 45 strand is offset, as at 21, to provide a bearing portion, and while off-set, its shape in cross-sectional area is not materially altered so that the loop 20 can swing freely 50 on it. The portion 21 is off-set in a direction at an angle to the plane of the frame, preferably at a right angle to said plane.

I claim:

A buckle comprising a frame made from a single piece forming a central strand and 55 forming loops of end strands and top and bottom strands, the two ends of the wire being looped around the central strand, the central strand having an off-set portion at the center, and at right angles to the plane 60 of the buckle, and a tongue pivoted to the off-set portion of the central strand and adapted to engage one of the flanking strands.

In testimony that I claim the foregoing, 65 I have hereto set my hand, this 31st day of December, 1921.

CARL E. PETERSON.
